UNITED STATES PATENT OFFICE

FRIEDRICH MERK, OF FRANKFORT-ON-THE-MAIN, GERMANY

MULTIPLE BRUSH SELECTOR WITH MECHANICAL BRUSH SELECTION

Application filed June 2, 1932, Serial No. 615,011, and in Germany June 2, 1931.

This invention relates to selectors for telephone installations, wherein a switch member is provided with a plurality of brush sets mounted on a common carrying support and 5 adapted to be rendered separately operative mechanically (for example by means of a push rod) for making contact with each of a group of line contacts, the rendering operative of the set of brushes coming into question 10 at any time being effected by a preceding corresponding setting of the switch member. Such a selector is described for example in my prior U. S. Patent No. 1,849,986 dated March 15, 1932 for an improved automatic 15 telephone switch.

The invention has for its object an improvement in such selectors and this result is obtained by adding a controlling switch which in one of its positions mechanically completes 20 or performs the function of rendering operative the set of brushes prepared for the selection.

The arrangement according to the invention relates to fundamentally new method of 25 use of a control switch, as this in addition to the usual switch operations (changing over contacts) is also used for mechanical switching operations. This enlarged method of use 30 of a control switch has above all, in connection with the multiple brush selectors above referred to, considerable advantages which are not obtained with the known selectors. In multiple brush selectors there are various 35 switching operations which when setting the selector switch member are subsidiary and cannot be carried out by the switch member itself. To this appertains in any case the completion of the brush selection, for which a separate electro-magnet was hitherto necessary, which, however, came into operation 40 temporarily only once on each use of the selector, and then could not be further used. This electro-magnet according to the invention is omitted or rather is replaced by the 45 electro-magnets of a valuable control switch. In addition it is avoided with certainty that during a selector setting, the arrangement for the mechanical selection of brushes is actuated a number of times and thus various sets 50 of brushes are successively rendered opera-

tive. This is prevented by the control switch in that it only permits of the completion of the brush selection in a predetermined switching position.

An example of construction of the invention is illustrated in the accompanying drawings. In these, a selector is shown as forming the basis of the example of construction, but the use of the invention is not limited to this selector type alone, since it extends also 55 to other multiple brush selectors (rotary selectors) with mechanical brush selection and preparation thereof by a preceding switch member setting.

In said drawings:

Figures 1 and 2 in front and side elevation respectively illustrate the complete selector constructed according to the invention.

Figures 3 and 4 are enlarged illustrations 70 in front elevation and longitudinal section respectively of the particularly interesting setting mechanism with control switch, omitting the parts in front of the switch and control member.

Figures 3a and 3b represent an indicating 75 device for the switch member, already illustrated in Figure 3, in different positions thereof.

Figure 5 shows an auxiliary switch member almost covered in Figure 3.

Figures 6 to 9 show the control member 80 and a push rod serving for inserting the brush sets in different operative positions.

Figure 10 is a view illustrating the coupling of the control member to the switch member when returning both.

Figures 11 to 13 are different views of an intermediate member (push member) for actuating the push rod.

In connection with the following description of one practicable construction, the 90 separate features of the invention will be described which reside particularly in the construction of the control switch making it suitable both for effecting the mechanical brush selection as also for other purposes 95 peculiar to multiple brush selectors.

Such a purpose occurs in connection with the regulation of the movement of an auxiliary switch member, associated with 100

the switch member, which is adapted only to partake of the movement of the switch member after a certain movement thereof. For the coupling of the auxiliary switch member with the switch member for this purpose, there would again be necessary a separate electro-magnet, which would be insufficiently used, in so far as it is required that the movement of the auxiliary switch member is to begin at a suitable predetermined phase of the switch member setting. This requirement is satisfied in the arrangement of a control switch according to the invention in that the control switch again causes in one of its positions the movement of the auxiliary switch member by the mechanical actuation of a coupling member.

A further problem solved by the control switch and auxiliary switch member is in connection with rendering the switch setting noticeable by an indicating device in multiple brush selectors with a switch member which is adjustable in the same direction before and after the brush selection. Such an indicating device is entirely novel for this type of selectors.

For operatively carrying out the idea of the invention, the drive for the selector switch member and for the control member is regulated, in the present example of construction, in a unitary manner so that for the setting of both devices (switch member and control switch), their own stored forces (gravity or springs) are used, and the renewal of these stored forces expended during the adjustment, is produced, for example, at the end of each use of the selector by a common driving device fed from the outside. The particular advantage of this arrangement resides in a far reaching relieving of the load of the electro-magnet which regulates the setting of the switch member and of the control switch, in that these have only to carry out a release operation, while the operative movements, even for the switch member and the control switch, are produced by the stored forces.

The selector consists of the following main parts: a contact field K, which is a part of a flat bank multiple; a brush slide B movable up and down in front of the contact field; a push rod S mounted adjacent the slide for selectively inserting the brush sets; a setting mechanism W for the brush slide with an included control switch and a return device R, constructed as a piston motor.

The three-row contact field K is divided into ten groups each of ten by three contacts. Similar contact fields of other selectors are located side by side. The drawings only show both upper and lower contact groups assembled in pairs. Between the contact fields are located bars 20 which hold together the bank multiple composed of partial banks, and a carrier 21 located underneath and for

the rest serving as mounting for the brush slides, the push rods and the setting mechanisms.

The brush slide B consists of a long plate 22 on which are mounted ten three-part brush sets 23. The slide is guided at the top and bottom at both sides in guide bearings 24, and is provided at the bottom with a forwardly projecting coupling projection 25 which, as will be described hereinafter, connects the slide to the setting mechanism. The plate 22 is provided with window-like openings 26 through which the brush springs can come into contact with the contact groups arranged behind them. The brush sets are however, normally raised from the contact field, and are each held in an inoperative position by a locking lever 27. The brush sets can be rendered operative separately by means of the push rod mounted adjacent the slide.

The push rod S is provided with ten pins 28, arranged in a line, near projections 29 of the locking levers which are arranged in a parallel line. The spacing of the pins on the one hand and of the locking levers and brush sets on the other hand are so dimensioned that after a lowering of the slide from the upper position (rest position) illustrated in Figures 1 and 2, successively through 1, 2 to 10 switch steps, the locking lever of the first, second to tenth brush set in the sequence from top to bottom has its projection just opposite one pin alone, while at the same time the corresponding brush set is spaced by one switch step in front of its contact group. If, therefore, after such a lowering of the slide the rod is turned with its pins to within a short distance of the slide, then a predetermined pin pushes the oppositely disposed locking lever out of the locking position, whereupon the corresponding brush set springs under the action of its springs into the operative position. On the further lowering of the slide the brush set then sweeps over its contact group until at the end of the contact path, a disengaging member (not illustrated) located at this point presses the brush set back into the inoperative position where it is again held by its locking lever.

The setting mechanism is a set of apparatus which can be completely removed and which is suspended by means of two pins 30 projecting laterally from its upper end in two bearing members secured to the bars. The setting mechanism combines on a long base plate 32, the switch member 33 constructed as a rack, and the control member 34 also constructed as a rack, together with their accessories.

The rack 33 is guided for easy sliding movement by means of bearing members 35, provided near its ends, in two slots 36 of the base plate. The length of the slots corresponds with the length of stroke of the

brush slide to which the rack is connected during operation by the insertion of the coupling projection 25 into a notch 37. The length of stroke with the assumed size and 5 group division of the contact field amounts to ten switch steps for the brush selection and the line selection which follows. A small additional amount in the length of stroke is provided for disengagement particularly of the lower brush sets.

The selector during setting is driven by the weight of the brush slide and of the rack. The release of the movement of both parts is effected by a ratchet pawl 39, engaging 15 with ratchet teeth 38 of the rack, which can be withdrawn from the rack by the electromagnet 40. By short or long energizations of the magnet there are produced short or long setting movements. In the case of long 20 movements, a centrifugal brake 42 engaging with driving teeth 41 of the rack limits the speed to a predetermined maximum value.

Between the rack and the base plate, as shown in Figure 4, there is provided an intermediate space in which there is slidably fitted in the same slots as the rack the auxiliary switch member 43 shown separately in Figure 5. The auxiliary switch member is suspended on the rack by a spiral spring 44 25 which imparts to it an upward pull. A stop 45 at the lower slot of the base plate limits the upward movement of the auxiliary switch member in such a manner that its upper end 46 maintains relatively to the upper bearing member 35 of the rack a spacing which is equal to ten switch steps. When the rack is lowered, the auxiliary switch member remains stationary by reason of the action of the correspondingly tensioned spiral spring 30 until the upper bearing member of the rack bears against the upper end of the auxiliary switch member. The rack on further lowering then moves the auxiliary switch member downwardly. The auxiliary switch member 45 may be moved by the rack also in the case of less than ten switch steps, if desired already after the first switch step by means of a spring pawl 47, secured to the auxiliary switch member and a toothed bar 48 secured 35 laterally to the rack. The spring pawl tends to bear against the toothed bar. The spring however, as will be described hereinafter, is first pressed by the control switch from the toothed bar and is only released for engagement with the toothed bar after the brush selection has been effected. Normally therefore, the auxiliary switch member partakes 40 of the setting movement of the rack and of the brush slide after the brush selection has been effected, at the latest however after the eleventh switch step.

The auxiliary switch member 43 operating in the manner above described, is used mainly for changing over contacts which are dependent on the commencement of selecting

the separate lines. Figure 3 shows, for example, a contact 49 which is opened after the first switch step of the selection of the separate line by the auxiliary switch member. In a similar manner the auxiliary switch member 70 may also actuate other contacts on subsequent switch steps calculated from the commencement of the selection of the separate lines.

Another valuable use of the auxiliary 75 switch member is shown by the number scale for reading off the setting of the switch member or of the brush slide. This case concerns a scale for selectors with group and separate line selection. Such indicating devices are known in connection with selectors having a switch member adjustable in two directions. In connection with multiple brush selections, however, wherein in the case of both selections a single switch member is 80 moved indiscriminately in the same direction, such indicating devices are not used. On the contrary multiple brush selectors require a separate arrangement of the indicating 85 device and the introduction of such a device is provided as the plurality of brush sets or the multiplicity of the switch member settings renders the correct meaning difficult.

The indicating device illustrated is in the 90 form of a two-part scale with a common pointer, so arranged that the scale 50 for the group selection is provided on the switch member 33, while the scale 51 for the separate line selection is stationary and the common 95 pointer 52 is secured to the said auxiliary switch member 43. Figure 3 shows the indicating device in the position of rest of the selector; Figure 3a shows the changed position after selecting, for example, the group 100 9, for which purpose the rack has been lowered through nine switch steps, and Figure 3b shows the modified position after further lowering the rack through five steps when the pointer has moved therewith through the 105 last step number, so that there is obtained the reading number 95.

The control switch (Figure 3) consists of a rod 34, arranged parallel to the switch member of the selector, which is also slidably 110 mounted in bearings 53 and is also drawn downwardly when setting by a spiral spring 54. The release of the rod is effected by a double locking pawl (escapement) 55 in combination with a toothed bar 56 provided laterally on the rod. The double locking pawl is held in the rest position illustrated in engagement with the toothed bar by its own spring, and is rocked by a magnet 57 which when 115 energized strikes by means of its armature 58, in the direction indicated by the arrow against the upper portion of the double pawl. The position of the control rod 38 shown in Figures 3 and 4 corresponds with the rest position. The release of the rod by the electro- 120

magnet 57 is independent of that of the selector switch member 33. Also the number and length of stroke of the setting steps of the control switch is capable of being suitably determined within the limits of the total stroke of the selector switch member. In the drawings, for the sake of simplicity, it is assumed that only four setting steps are provided for the control switch, of which two appertain to the armature attraction and two to the fall of the armature of magnet 57, the first switch step being larger than the succeeding steps for a reason to be described hereinafter.

The control rod 34 is provided at its lower end with two unequal cams 59 and 60 as an example for the use of the control switch for changing over contacts.

Above the toothed bar 56, there is provided on the control rod an upwardly directed one armed lever 61 which in the rest position of the control rod (Figures 3 and 6), is pressed towards a base plate against a spring 64 by an outwardly bent arm 62 engaging with a member 63 having an upwardly inclined surface. The lever is also provided with a lateral projection 65 embracing the control rod, which on the inner side of the control rod has the shape of a ratchet tooth as indicated by the broken lines in Figure 6.

When the control rod slides downwardly from the rest position in Figure 6 the lever 61 moves from underneath the member (63) with the inclined surface away from the base plate as shown in Figure 7. The spring-pawl 47 shown in Figs. 3 to 7 and which likewise moves from the base-plate, follows said lever. This spring-pawl (47) snaps into the rack 48. Thus it will be apparent that the control switch on reaching the inoperative position, directly couples the auxiliary shift-member 43 with the rack 34 by the release of said spring-pawl.

It will now be shown how the control switch when leaving the rest position at the same time mechanically operates the push rod S. The actuation consists, in accordance with what has been described above, in a single rearward rotation of the rod. This movement is transmitted to the rod by a push lever 66 mounted near the upper end of the setting mechanism and on the rear side thereof. Figure 3 shows the position of the lever in broken lines. When hanging the setting mechanism in its operative position, the lever 66, according to Figure 12 bears against an inclined forwardly directed pin 67 on the push rod S terminating behind the base plate 32. A window 68 in the base plate (Figure 3) enables the engaging position of the lever 66 and pin 67 to be seen during operation. Figure 11 shows the push lever and the rod in plan, while Figure 13 shows the rotation of the rod when the push lever moves downwardly.

The push lever 66 during the first falling step of the control rod is pulled downwardly with said rod indirectly by an engaging pawl 69. When the push lever has reached the position shown in Figures 7 and 13, the engaging pawl strikes with a short arm 70 against the lower edge of the window (68) of the base plate. While the control rod continues its movement for a short distance, the engaging pawl is disengaged by a rapid rocking movement from the push lever (Figure 8), whereupon the latter and the push rod spring back immediately under their own spring forces into the rest position. Thus the brush engagement (together with the above mentioned coupling of the auxiliary switch member and the control rod) is completed at the first response of the control magnet 57. For the two operations it is immaterial whether the control magnet now falls immediately or remains energized for a longer period. This means that the carrying out of the further falling steps of the control switch (Figure 9) can take place at any suitable time intervals.

For the purpose of returning the selector and control switch, the brush slides and the rack must always fall to their lowest position. This is effected in a simple manner by continuously energizing the electro-magnet 40. When the brush slide has reached its lowest position it bears with its weight on the rod 71 of a piston motor R, actuated by compressed air and acting as a return device. This arrangement is known per se and acts in such manner that on the occurrence of the piston load by a slide, a valve reversal takes place which allows compressed air from a pipe 72 to flow under the piston. The piston then raises the slide, the rack and the control rod simultaneously into their initial position. The movement of the control rod during the return movement is effected by means of the rack. The securing screw, shown in Figure 3, of the upper bearing member of the rack has a pin like extension 73 which on the downward movement of the rack moves on the chain dotted line a—b indicated in Figure 10 and finally overruns the projection 65, similar to a ratchet pawl, of the lever 61 whereby this temporarily escapes and then comes in front of the pins 73. During the upward movement of the rack the pin moves the control switch upwardly therewith until by the slipping of the lever 61 under the member 63, according to Figures 3 and 6, the lever moves away from the pin, that is to say disengages the slide from the rack. The rack and slide then continue to move alone. The auxiliary switch member 43 alone moves upwardly under the action of the spiral spring 44 until the stop 45 limits its movement whereupon the partially expanded spiral spring is tensioned by the further upwardly moving rack. Shortly before the limit of the stroke of the auxiliary switch member is reached, the spring pawl 47 has been disen-

gaged from the toothed bar 48 by the projection 65 of the lever 61 slipping over the member 63, which takes place shortly before the end of the stroke of the auxiliary member 5 so as to withdraw said pawl from said rack. When the slide and rack have reached their initial position, the piston in known manner shuts off the supply of compressed air, whereupon the piston under the action of gravity 10 again moves downwardly, while the slide and rack are held by the ratchet pawl 39 of the disengaged electromagnet 40 until the next use of the selector.

By the description it has been shown that 15 the main object of the invention (simplification of a selector for group and single line selection actuated by a control switch) is fully fulfilled by the steps which are taken (independent storing force setting and common foreign force return of the selector and control switch member) in that for all the numerous problems inherent in the adjustment of the said selectors, the result is achieved with inexpensive storing forces 20 (gravity and springs) which require little space. In particular, the application of this fundamental idea of the invention to multiple brush selectors of bar form has been carried out in such detail that from this description 25 other analogous possibilities of use of the invention can be readily effected.

I claim:—

1. A multiple brush selector with mechanical brush selection, comprising a contact field, a movable switch member carrying a plurality of brush sets, a setting mechanism; said setting mechanism being connected to a control switch adapted to actuate contacts in various positions, and means for mechanically actuating a brush set selected by a setting movement of the switch member so as to move it into the operative position for making contact with the contact field; said control switch mechanically actuating the means 40 for actuating a brush set in one of its positions.

2. A multiple brush selector with mechanical brush selection, comprising a contact field, a movable switch member carrying a plurality of brush sets, a setting mechanism, an auxiliary switch member in said setting mechanism adapted to be moved together therewith after a certain movement of the switch member, a control switch connected to the setting mechanism and adapted in various positions to actuate contacts, means for mechanically actuating a brush set selected by a setting movement of the switch member so as to bring it into the operative position 55 for making contact with the contact field, and means for coupling the auxiliary switch member with the switch member; said control switch in one of its positions mechanically actuating the means for mechanically actuating a brush set and mechanically con-

trolling in one of its positions the means for coupling the auxiliary switch member.

3. A multiple brush selector with mechanical brush selection, comprising a contact field, a movable switch member carrying a plurality of brush sets; said switch member being adjustable in the same direction for selecting a brush set and for selecting a contact of the contact field, a setting mechanism, an auxiliary switch member in said setting mechanism adjustable together with the switch member after a predetermined movement thereof, means for coupling the auxiliary switch member with the switch member, a two-part scale one part of which is secured 70 to the switch member and is movable therewith and the other part of which is locally secured, and a pointer secured to the auxiliary switch member and moving therewith.

4. A multiple brush selector with mechanical brush selection, comprising a contact field, a movable switch member carrying a plurality of brush sets, a stored force for moving the switch member, a setting mechanism regulating the movement of the switch member; said setting mechanism being connected to a control switch adapted in various positions to actuate contacts, a stored force for moving the control switch, a magnet for regulating this movement of the control switch, and means for mechanically actuating a brush set selected by a setting movement of the switch member for bringing it into the operative position for making contact with the contact field; said control switch 100 mechanically controlling the means for actuating a brush set in one of its positions.

5. A multiple brush selector with mechanical brush selection, comprising a contact field, a movable switch member carrying a plurality of brush sets, a stored force for moving the switch member, a setting mechanism regulating the movement of the switch member; said setting mechanism being connected to a control switch adapted in various positions to actuate contacts, a stored force for moving the control switch, a magnet for regulating this movement of the control switch, means for mechanically actuating a brush set selected by a setting movement of the switch member for bringing it into the operative position for making contact with the contact field; said control switch mechanically controlling the means for actuating a brush set in one of its positions, and a driving device applied outside for renewing the stored forces expended when setting the switch member and the control switch.

6. A multiple brush selector according to claim 5, wherein said driving device moves 115 the switch member and the control switch in a direction opposite to the setting movement.

7. A multiple brush selector with mechanical brush selection, comprising a contact field, a movable switch member carrying a 130

- number of brush sets, a stored force for moving the switch member, a setting mechanism regulating the movement of the switch member; said setting mechanism being connected to a control switch adapted in various positions to actuate contacts, a stored force for moving the control switch, a magnet for regulating this movement of the control switch, means for mechanically actuating a brush set 10 selected by a setting movement of the switch member for bringing it into the operative position for making contact with the contact field; said control switch mechanically controlling the means for actuating a brush set 15 in one of its positions, a driving force applied at the outside for renewing the stored forces expended when setting the switch member and the control switch; said driving device acting directly on the switch member and moving the same in a direction opposite to the setting movement, and automatically operating coupling members for connecting the control switch to the switch member during the return movement thereof to initial 20 position. 8. A multiple brush selector with mechanical brush selection, comprising a contact field, a movable switch member carrying a plurality of brush sets, a setting mechanism; 25 said setting mechanism being connected to a control switch adapted in various positions to actuate contacts, and means for exerting a temporary push upon a brush set selected by a setting movement of the switch member for bringing it into the operative position for making contact with the contact field; said means including intermediate members actuated by the control switch in one of its positions and automatically released from the control switch after exerting the push on the brush set. 30 9. A multiple brush selector according to claim 8, wherein said switch member and said setting mechanism are formed as separate exchangeable sets of apparatus, and said means for exerting a push is mounted in a stationary position adjacent the switch member, while said control switch and said intermediate members are structurally connected to the setting mechanism. 35 10. A multiple brush selector with mechanical brush selection, comprising a contact field, a movable switch member in the form of a rod carrying a plurality of brush sets, a setting mechanism constructed in elongated form; said setting mechanism being connected to a control switch and said control switch being constructed in the form 40 of a rod in accordance with the elongated shape of the setting mechanism and being adapted in various positions to actuate contacts, and means for mechanically actuating a brush set selected by a selecting movement 45 of the switch member so as to bring it into operative position for making contact with the contact field; the aforesaid control switch mechanically actuating the means for actuating a brush set in one of its positions. 50 FRIEDRICH MERK. 70 75 80 85 90 95 100 105 110 115 120 125 130
